UNITED STATES PATENT OFFICE.

OTTO G. ZERSE, OF MOUNT VERNON, INDIANA.

COMBINATION DESK AND KITCHEN-CABINET.

1,221,498.

Specification of Letters Patent.

Patented Apr. 3, 1917.

Application filed August 21, 1915. Serial No. 46,684.

To all whom it may concern:

Be it known that I, OTTO G. ZERSE, a citizen of the United States, and residing at Mount Vernon, in the county of Posey and 5 State of Indiana, have invented a certain new and useful Improvement in Combination Desks and Kitchen-Cabinets, of which the following is a specification.

This invention relates to a combined desk 10 and culinary cabinet adaptable especially for the use of students or others occupying limited quarters.

The invention has for its objects to provide a comparatively simple, inexpensive 15 article of furniture which combines, in a practical and desirable manner, the several functions of a desk, dining table, culinary stand and cabinet, and which, under normal conditions, presents an attractive appearance 20 and affords ample and convenient storage space for utensils and other necessary culinary appurtenances.

Further objects of the invention are to provide a device of this character wherein 25 the various culinary appliances may be effectively concealed from view, and, at the same time, be readily accessible for use, and one which, when functioning as a table, offers a seating capacity sufficient for a number of 30 persons.

With these and other objects in view the invention comprises the novel features of construction and combination of parts more fully hereinafter described.

35 In the accompanying drawings;

Figure 1 is a front elevation of the furniture article embodying the invention and showing the same arranged normally as a desk;

40 Fig. 2 is a top plan view showing a converted arrangement to form a dining table;

Fig. 3 is a view similar to Fig. 1, the doors being open to expose the cabinet compartments to view;

45 Fig. 4 is a vertical transverse section taken on the line 4—4 of Fig. 1, and viewed in the direction of the arrow;

Fig. 5 is a similar view taken on the line 5—5 of Fig. 1;

50 Fig. 6 is a detail sectional view taken on the line 6—6 of Fig. 1; and

Fig. 7 is an enlarged detail view in section, taken on the line 7—7 of Fig. 2.

Referring to the drawings, it will be seen 55 that the device, which is designed upon the

lines of an ordinary flat topped desk, embodies a pair of cabinet sections 1 and 2 equipped with doors 3 and suitably spaced relatively to provide a central space 4, said sections being connected by a main top or 60 top frame 5 and a base 6 mounted on suitable casters 7, while provided at the upper end of the space 4 is a drawer compartment containing a pair of drawers 8 arranged end to end to open respectively at opposite sides 65 of the desk, as is usual in such furniture.

The cabinet section 1 is, in accordance with this invention, sub-divided by a horizontal partition 9 and a vertical partition 10 into a lower compartment 11 and a pair of upper 70 compartments 12 and 13, of which the compartment 13 receives a removable ice box 14 of suitable form and construction, and having, preferably, a drain cock 15 and a hand pull 16, while the section 2 is sub-divided by 75 a partition 17 into a lower compartment 18 and an upper stove compartment 19 adapted to receive a gas or other stove 20, as shown, there being provided in the compartment 18 a shelf or tray 21 and in compartment 11 a 80 similar shelf or tray 22. These trays, which are designed to receive and carry foodstuffs or utensils stored in the respective compartments, are slidably mounted on the base 6, and are adapted to be drawn forward to a 85 position permitting ready access being had to their contents, the tray 21 being made wholly removable from its compartment, while the tray 22 may be only partially withdrawn and is guided in its movements 90 by lateral fore and aft guide rails 23, which co-operate with a stop piece 24 to limit such outward movement of the tray.

The main top 5, which is covered with zinc or other noncorrosive sheet metal 25, 95 is provided with an enlarged opening 26 centered above the stove compartment 19 and with a longitudinal slot 27 eccentrically located at a point adjacent the rear edge, and to the left of the medial line of, said 100 main top, there being mounted upon the latter a cover 28 slidably and pivotally held in place by means of a countersunk pivoting member or bolt 29, entered through slot 27 and threaded to receive a retaining nut 30, 105 said cover which constitutes in effect an auxiliary top for the desk, and a closure for the opening 26, being of a size to wholly cover and project marginally beyond the top 5, and is adapted, as a result of the eccentric loca- 110

tion of its pivotal connection 27-29, to swing to the converted position, illustrated in Fig. 2, to serve as a dining table.

In practice the culinary appurtenances, such as foodstuffs, utensils and dishes, are normally stored in the several compartments 11-12 and 18, and the stove 20 housed in its compartment 19, with the doors 3 closed and the part 28 in position to cover the top 5. 10 The furniture article is now adapted for use as a desk, in the ordinary manner, and under such conditions the space 4 will, as usual, accommodate the feet and limbs of the person seated at the desk. When the device is to 15 be used for culinary purposes, the cover 28 is swung to the position, as in Fig. 2, thus uncovering the stove 20 for use and exposing a part of the metal covered top 5, for the reception of hot dishes and utensils. As 20 the culinary operations proceed, access may be readily had to utensils and food stuffs, as needed, by opening the doors 3 and drawing the ice box 14 and trays 21 and 22 forward out of their several compartments, as 25 heretofore explained, and as will be readily understood. After preparing the meal it may be served on the part 28, which, when arranged as in Fig. 2, subserves the functions of a dining table and offers ample seating 30 capacity for comfortably seating a number of persons. In this connection, it is to be observed that, as a result of the peculiar form and arrangement of the pivotal connection 27-29, the cover 28 may be brought 35 to a position for its ends to project equidistantly beyond the sides of the top 5, and further that, through the provision of slot 27, the cover 28 may be shifted bodily to the left, thus to properly project beyond 40 and overhang the adjacent end of the top 5 and afford a seating space at the table at this point.

It is apparent that under this invention there is produced a furniture article which, 45 in subserving its various functions, economizes space, and is, therefore, highly adaptable for use by those occupying limited quarters, and further that the said article will, under normal conditions, present an attractive, ornamental appearance, while, at 50 the same time, affording ample storage for, and concealment of, all the necessary culinary appurtenances.

In attaining these objects, the invention 55 is not necessarily limited to the details of construction herein shown and described, inasmuch as various minor changes may be made in such details, without departing from the spirit or scope of the invention.

60 Having thus described the invention, what is claimed is:

1. An article of furniture, comprising a vertical end cabinet having a main top

formed and arranged to normally provide a seating space at one side of said cabinet, 65 said cabinet being formed with a vertical stove receiving well or compartment opening through said top, a cover constructed and arranged to normally overlie said top for closing said compartment and adapting 70 said article for use as a desk, and means connecting the cover on said top for movement to a position to overhang the sides and one end of said top to form a dining table.

2. An article of furniture combining a 75 desk, kitchen cabinet and dining table and comprising a pair of vertical end cabinet sections arranged to provide a seating space between them, a top connecting said sections, one of said cabinet sections being formed 80 with a vertical, stove receiving well or compartment opening through said top, a cover coextensive with and constructed and arranged to normally overlie said top for closing said compartment and adapting said 85 article for use as a desk, and means connecting the cover on said top for movement to a position to overhang the sides and one end of said top to form a dining table.

3. An article of furniture combining a 90 flat top desk and a dining table, comprising a desk body, a unitary and uninterrupted cover mounted thereon to cover the same, and means connecting said cover to said body, constructed and arranged to permit 95 said cover to move to a position cross-wise of said body and overhang the same along a plurality of its sides to provide seating spaces, substantially as described.

4. An article of furniture combining a 100 flat top desk and a dining table, comprising a desk body, a unitary and uninterrupted cover mounted thereon to cover the same, and means connecting said cover to said body, constructed and arranged to permit 105 said cover to move to a position cross-wise of said body at one end thereof and overhang the same along three sides to provide seating spaces, substantially as described.

5. An article of furniture combining a flat top desk and a dining table, comprising a desk body, a unitary and uninterrupted cover mounted thereon to cover the same, and a combined pivotal and sliding connection between said cover and said body intermediate the ends of said cover and adjacent one side of said body, constructed and arranged to permit said cover to be moved to a position to overhang said body 115 along a plurality of its sides and provide seating spaces, substantially as described.

In testimony whereof I affix my signature this 6th day of August, 1915.

OTTO G. ZERSE.
